CLAIM

The ornamental design for a shoe, as shown and described.

DESCRIPTION

FIG. 1 is a top, front, left side perspective view of a shoe according to our new design;

FIG. 2 is a left side elevation view of FIG. 1;

FIG. 3 is a right side elevation view of FIG. 1;

FIG. 4 is a front elevation view of FIG. 1;

FIG. 5 is a rear elevation view of FIG. 1;

FIG. 6 is a top plan view of FIG. 1; and,

FIG. 7 is a bottom plan view of FIG. 1.

The long dash-short dash broken lines represent boundaries of the claimed design and form no part of the claimed design. The evenly spaced broken lines depict portions of the shoe that form no part of the claimed design.

1 Claim, 7 Drawing Sheets
